United States Patent Office

Des. 220,548
Patented Apr. 20, 1971

220,548

ELECTROPIANO

Robert L. Ferris and Daniel W. Martin, Cincinnati, Ohio,
assignors to D. H. Baldwin Company, Cincinnati, Ohio

Filed June 24, 1969, Ser. No. 17,850

Term of patent 14 years

Int. Cl. D17—01

U.S. Cl. D56—9

Fig. 1

FIG. 2.**FIG. 3**

FIG. 1 is an angular perspective view of an electro-piano embodying our new design.

FIG. 2 is a front elevational view thereof.

FIG. 3 is a side elevational view thereof.

The back of the electropiano not shown, is conventional.

The side not shown is the same as the side shown.

We claim:

The ornamental design for an electropiano, substantially as shown and described.
